YIELDING CONTACT UNIT

Fred H. Cole, Glendale, Calif., assignor, by mesne assignments, to General Electric Company, a corporation of New York

Application June 28, 1937, Serial No. 150,662

3 Claims. (Cl. 200—166)

My invention relates to electrical devices, more particularly circuit breakers, and is directed to an improved form of replaceable contact unit for a circuit breaker and the like.

5 In a circuit breaker for large currents and high potentials, it is highly essential that the circuit-controlling contacts close together in a positive manner with absolutely no bounce to avoid a destructive welding action. It is also 10 essential, when a plurality of contacts are carried by one operating member, to insure that the abutment of one pair of contacts together will not prevent proper abutment of the remaining contacts associated with the operating member. 15 For both of these reasons a yielding mounting is desirable for at least one contact in each co-operating pair of contacts, such yielding mounting being commonly provided by a relatively heavy spring means.

20 In the manufacture or repair of such mechanism, two adjustments are involved, the spacial adjustment of the two contacts of a pair, and the pressural adjustment of the pair, the first adjustment determining the point in the closing movement of the circuit breaker at which the complementary contacts meet, and the second adjustment determining the pressure developed between the contacts in the closing movement beyond that point. It is generally 25 found convenient to associate one of these adjustments with one contact of a pair and the other adjustment with the other contact, both for simplicity in manufacture and to keep one adjustment means from interfering with the other. A feature of my invention is that it provides for associating both of these adjustments with the same contact, which contact may be either the stationary or the movable contact of a pair of contacts.

30 One object of my invention is to simplify the manufacture and repair of a circuit breaker by providing a bench-assembled self-contained contact unit for detachable installation in a circuit breaker with minimum adjustment required.

Another object is to provide such a unit in which the yielding feature is pre-adjusted, not requiring adjustment or manipulation in the assembly of the unit to the circuit breaker.

35 Another object of my invention is to provide both the yielding feature and the means for spacial adjustment in the same contact, without conflict with each other. In the preferred form of my invention I propose to achieve this object by, in effect, mounting the yielding means on

the spacial adjustment to be moved bodily thereby without affecting the character of the yielding action.

The conductors of a circuit breaker, particularly in the vicinity of the open contacts, should be smooth and free from projections, whereas adjustment means generally involves irregular configurations. Further irregularity of contour arises from the necessity, usually, of providing a flexible but direct connecting means between a 10 movable contact and its associated conductor, especially when the contact is spring-mounted for movement relative to the conductor. One object of my invention is to provide a contact unit in which all such undesirably irregular members are effectively shielded.

With reference to the yielding feature itself, I have the objects of providing a simple means of pressure regulation in the manufacture of the unit, and of achieving the advantages of a relatively long spring acting between the contact and its associated conductor without providing a corresponding distance between the contact and conductor.

The above and other features and advantages 25 of my invention will be apparent in the detailed description to follow:

Broadly described, my invention comprises a body adapted for releasable and adjustable attachment to a conductor in combination with a 30 contact element yieldably extending from said body.

In the drawing, which is to be considered as illustrative only,

Fig. 1 is a fragmentary sectional view of a 35 circuit breaker showing structure associated with two cooperating contacts, the parts being shown in the open position of the device;

Fig. 2 is similar to Fig. 1 with the parts in 40 closed circuit position;

Fig. 3 is a cross-section taken as indicated by the line 3—3 of Fig. 2; and

Fig. 4 is a section taken as indicated by the line 4—4 of Fig. 1.

For the purpose of exemplifying the principles 45 involved, I shall describe my invention as specifically adapted to a circuit breaker employing an oil dielectric, more particularly a circuit breaker of the type disclosed in my copending application Serial No. 146,786, filed June 7, 1937, 50 patented May 2, 1939, Number 2,156,450, entitled "Method of and apparatus for interrupting an electric circuit"; but it will be understood that the principles of my invention are also applicable to other types of switching devices.

The drawing shows an arc quenching member 10 movable with respect to a plurality of relatively fixed contact elements 11, the arc quencher having a plurality of contact elements 12 forming pairs with the contact elements 11, only one of the pairs being shown in the drawing. The contact elements 12 are interconnected by a suitable conducting member 13 to which the contact elements may be secured by screw-threaded engagement, as shown. Each of the contact elements 12 is fixed at the inner end of a passage 14 of the arc quenching member that is adapted to receive the corresponding contact element 11. In the open circuit position of the parts, the arc quenching member 10 is in spaced relation to the contact element 11, as is shown in Fig. 1, and in the closed circuit position of the parts the arc quenching member is moved sufficiently toward the contact element 11 to provide pressural engagement of the two contacts at the inner end of the passage 14, as shown in Fig. 2.

In the construction chosen for illustration, the contact element 11 is associated with an electrical conductor 15 that extends downward through a porcelain tube 18 and terminates in a permanent end-member generally designated 19, the end-member being adapted for the purposes of my invention.

I propose to provide as a part of my unit a body releasably attachable to the end-member 19 and adapted to form therewith a chamber or shielded space 20 for housing various irregular portions of the unit, whereby the exterior of the unit may present a smooth surface effective for equalization of electrostatic stress distribution. For such purpose I may shape the end-member 19 to present an inverted cup having an internally threaded cylindrical portion 21 and an end wall 22 having a suitable vent aperture 23. The body, generally designated 25, is also cup-shaped and has a cylindrical wall 26 with exterior threads for engagement with the cylindrical wall 21 of the end-member 19 whereby the body 25 may be adjusted axially with respect to the end member 19. For the purpose of fixing the body at an adjusted position, a suitable lock-nut 27 may be provided. Preferably, the bottom of the body will comprise a separable member in the form of a bushing 28.

Integral with the cylindrical wall 26 and extending inwardly therefrom are a lug 30 at an upper level and a finger 31 at a lower level, the finger terminating in a downwardly extending tubular end 32. In the preferred form of my invention, the contact element 11 is a hollow member preferably tubular in configuration, the tubular member slidably embracing at its inner end the cylindrical portion 32 of the finger 31 and being in turn slidably embraced by the bushing 28. It will be apparent that the portion 32 of the finger and the bushing serve as cooperating guides to keep the contact element 11 in proper alignment.

Some provision is required for limiting the outward movement of the contact element 11 with respect to the body 25. For this purpose a collar 33 may be fixed on the contact element 11 near the inner end thereof at a position permitting a substantial range of movement of the contact between a position with the collar abutting the bushing 28 and a position with the inner end of the contact stopped by the finger 31. Preferably, this range of movement will be sufficient to accommodate not only the yielding action de-

sired, but also an additional substantial tolerance to avoid the necessity of close adjustment.

In the preferred form of my invention the yielding means for urging the contact element 11 toward its extended position comprises a helical expansive spring 35 within the contact element in compression between the outer end wall 36 of the contact element and the face 37 of the finger end 32. It is to be noted as a feature of my invention that a relatively long spring for acting between the body of the unit and the contact element is accommodated by the space within the contact element, the virtue of such an arrangement being that I incorporate in the operation of my device the desirable characteristics of a relatively long spring without affecting the compactness of my unit. In one embodiment of my invention, for example, I arrange for a minimum compression of twenty pounds on the part of the spring 35 in the open position of the circuit breaker and I select a spring of such character that additional compression of approximately three-eighths of an inch caused by closing the circuit increases the pressure of the spring to approximately fifty pounds. Also, I provide an additional permissible movement of three-eighths of an inch on the part of the contact element 11 for tolerance of adjustment.

In the bench assembly of the contact unit, variations in the characteristics of individual springs 35 may be offset by means in the form of discs 38 adapted to be placed in the closed end of the contact element as spacer means for increasing the compression of the spring 35. Such spacer means may also be employed for the purpose of increasing the pressure of the springs to meet the requirements of particular installations.

For direct electrical connection between the unit body 25 and the contact element 11, I provide a pair of flexible conductors, such as laminated conductors 39 and 40. The conductor 39 has its lower end fixedly seated in a transverse groove 41 of the collar 33 and its upper end engaged by a suitable screw 42 in the finger 31. In a similar manner the contact 40 has its lower end seated in a second transverse groove 43 in the collar 33 and has its upper end engaged by a suitable screw 44 in the lug 30.

I have provided in the manner described a replaceable contact unit that may be installed by simply threading it to the complementary end-member of the circuit breaker, special adjustment being provided by the threaded engagement and fixed by the cooperating lock-nut. The yielding characteristic of the contact unit is fixed at the time of manufacture, both with respect to the amount of yielding movement and the pressure resisting such movement, so that such matters do not require the time and attention of the person who installs the contact unit. The result is not only a saving of time in the installation of the unit, but also a uniformity of contact adjustment.

It will be apparent from my disclosure that changes and modifications of the specific form set forth may be made without departing from the principles involved, and it is to be understood that I reserve the right to all such changes and modifications that properly come within the scope of my appended claims.

I claim as my invention:

1. A contact unit for a high voltage circuit breaker having a lead-in conductor, said unit comprising: a hollow body adapted for substantially rigid adjustable attachment to said conductor; said body forming with said conductor a

- substantially smooth outer surface for shielding purposes; means to lock the connection between the body and conductor at a selected adjustment; a contact element retractably extending from the body; yielding means acting between the contact element and the interior of said body to urge said contact element toward its extended position through an end wall of said body; and conductor means within said body flexibly interconnecting said body and contact element.
5. 2. A contact unit for a high voltage circuit breaker having a lead-in conductor terminating in contact adapter structure, comprising a hollow shielding body of conducting material mounted on said adapter structure, said shielding body being rigidly attached to said adapter and bodily adjustable along the longitudinal axis thereof, a relatively movable contact element slidably mounted in an end wall of said shield and biased 10 outwardly therefrom, means for adjusting the bias on said contact element and a flexible conductor interconnecting said shield and contact element, said flexible conductor and the reentrant portion of said contact element being wholly surrounded by said shield in the operative position thereof.
3. A contact unit for a high voltage circuit breaker having a lead-in conductor terminating in a contact adapter, said adapter having a depending annular flange, comprising a cup-like shield of conducting material adapted to be rigidly connected in substantially flush-surface relation to said flange, means for adjusting said shield with respect to the longitudinal axis of said adapter, a contact element mounted in said shield and extending through the end thereof opposite said adapter, means for resiliently biasing said contact element towards the extended 15 position, said contact element and resilient means being wholly mounted within said shield, and a flexible conductor electrically connecting said shield and element whereby the aforesaid contact and shielding structure can be detached as a unit 20 with respect to said adapter.
